OIL BURNER

Percy Vincent Knapp, Alfred Irvine Senior, Maxwell McNabb, and Edward Hans Tui Bensemann, Motueka, New Zealand

Application April 23, 1937, Serial No. 138,662
In New Zealand May 5, 1936

4 Claims. (Cl. 158—91)

This invention relates to a burner construction designed for use with oil fuels, and in any of the circumstances in which such types of burners are generally employed, as for instance in the 5 heating of domestic cooking ranges or stoves, and in the heating of drying chambers, and other such like operations.

The invention is concerned with a construction of burner apparatus under which the oil fuel is 10 fed to a burner contained within a combustion chamber to which air is admitted to obtain the vaporization and combustion of the oil is admitted and in which the flames of combustion have air admitted thereto as they pass away from the combustion 15 chamber in order to increase the intensity of the heat produced thereby.

The improvements forming the invention have been devised with the objects of providing a new construction and combination of parts whereby 20 these effects may be produced and whereby a more effective mixture of the vaporized oil and air to obtain the combustion, is obtained, and also whereby provision is made for a supply of water vapour being drawn in with the air to support 25 the combustion.

In fully describing the invention reference will be made to the accompanying sheet of drawings, in which:—

Figure 1 is a plan of the whole burner and its 30 casing enclosure, the latter being shown in section.

Figure 2 is an outer end elevation thereof.

Figure 3 is a longitudinal section thereof.

Figure 4 is a cross section taken on the line 35 4—4 of Figure 3 and looking to the right of such line.

Figure 5 is an enlarged cross section of the inner end of the burner body and of the casing enclosure, showing the arrangement of the admission ducts for the air for admixture with the 40 burner flames.

In giving effect to the invention, a cylindrical burner chamber 10 is combined with a suitable flat face plate 11 to extend horizontally therefrom on its front face and also to extend for a distance on its rear face to thereby adapt itself for entry into the sphere into which the burner flame is to be drawn by reason of the draught caused in such sphere. This face plate 11 may 45 conveniently be used to secure the burner upon the stove front or furnace or other apparatus with which the burner is combined for the heating thereof. It also serves as a means for attaching the enclosure casing 12 which will be 50 hereinafter more fully described. The outer end

of the burner chamber is closed by a suitable closure 13 which may be made removable if so desired. The burner is designed to be employed in circumstances under which an air draught is induced to act from the rear end of the chamber 5 by natural draught or forced draught, as may be desired.

The chamber 10 is enlarged in diameter at about the middle of its forward part and formed in the top portion with an opening 14 extending around its top. A lid 15 is provided to fit within such opening to cover it. This opening is provided for purposes of access to the burner pot in lighting up and in attention generally to the burner. The burner pot, which is shown at 16, 15 is attached to the bottom of the enlarged part of the chamber being formed by a pan having a raised edge, attached to a supporting stem 17 which projects the pan upward within the chamber area so that the air for combustion may pass 20 around and over the pan on all sides. The stem 17 may have a drain hole 18 leading down through it to outside the chamber, for draining away any overflow of oil from the burner. The burner pan is lined with any suitable refractory absorbent material, such as asbestos, and has the oil supply dropped into it from a drip feed pipe 19 leading down through an opening formed in the chamber top and connected with any 25 suitable overhead source of supply having ordinary control means.

The lid 15 is made with an air entry aperture 20 extending transversely across it, and preferably shaped of the triangular formation shown in Figure 1, and with its edges tapering downwardly and inwardly as shown in Figure 3, in order that as air is drawn down through this opening, it will be distributed over the area of the chamber and around the burner pot 16 with a whirling action, to thereby more effectually cause 35 the combustion of the oil that is fed to such pot. Air also will be drawn down through the opening through which the tube 19 passes, to impinge more directly upon the pan surface and support the combustion of the oil.

The chamber 10, outside the face plate 11, is shaped with an external annular enlargement 21, and a number of air ducts 22 are formed in this enlarged portion to extend from its front face and then radially inward to open into the 40 inside of the chamber 10. These ducts are disposed at distances apart all round the chamber and are provided to cause air currents to enter under the inductive force of the draught acting in the back end of the burner chamber. These 45

currents thus whirl round the chamber area and mixing with the flames coming from the burner pot, serve to increase the heat thereof. The manner of forming and arranging these 5 ducts is shown more fully in the enlarged detail drawing Figure 5.

A register plate ring 24 is provided to surround the chamber and to fit against the front face of the enlargement 21, such ring being made to 10 cover the ducts 22 more or less by forming it with openings which correspond in number, position and size, with the duct openings. By turning this ring on the chamber therefore the amount of air to be admitted through the ducts may be regulated at will and thus the combustion effects controlled as required.

The burner chamber thus made and operating is enclosed in a cylindrical casing 12 that is constructed to surround it and leave an annular air 20 space between them, such casing at its rear end fitting around the enlargement 21 and being attached to the face plate 11 at such rear end by means of suitable fastenings, as for instance the radial lugs 26 engaging the plate and the 25 screws 26^a passing through the lugs into the plate. This casing is closed at its front end. It is made with an opening 27 in its top that is covered by a cover plate 28, which when removed, will allow of the chamber lid 15 being lifted out 30 to permit of access to the burner pot when starting the burner. Air is allowed to enter through this opening such air preferably being led into it through passages 29 extending up its outside wall on each side and connecting with such opening 27. This will cause the air to be warmed to some extent by reason of its flowing over the 35 wall of the casing, which becomes heated by radiant heat from the burner chamber. The air thus entering the casing, will supply the burner 40 through the air aperture 20 and the ducts 22, its passage within the space around the chamber 10 causing it to be heated to a high temperature before passing through the ducts 22, so that it 45 mingles more efficiently with the flames passing from the burner pot, to increase the combustion temperature thereof.

The casing 12 is formed along one side with an open top gutter 30 in which a supply of water may be maintained through a drip pipe 31. 50 This water will be heated by the burner heat to produce a steam or vapour which will be carried with the air through into the burner chamber, to thus aid in the complete combustion of the carbon contents of the combustion products. In 55 some cases the gutter may be formed along the outside of the burner chamber.

The casing 12 may also be made with a sump 32 at its forward end, into which any excess of water or overflow of oil from the burner pot will 60 gravitate, such sump being provided with a draining nipple 33 to drain the said liquids away.

This burner is started in the manner commonly used in starting up burners of this type, that is by placing an igniter kerosene saturated mass 65 in the burner pot to heat it to the extent necessary to ensure of the vaporization of the oil fuel fed to such pot. This operation may be readily carried out by removing the cover 28 and lifting out the lid 15. Repairs to this pot may also be 70 carried out by access through the openings thus provided for.

We claim:—

1. An oil fuel burner comprising a horizontal

cylindrical burner chamber having a closed front end and an open rear end and provided with a top opening, a lid covering said top opening, said lid having an air entry aperture therein, said cylindrical chamber also being provided near its rear end with a number of air entry ducts disposed at circumferentially spaced intervals and opening radially into the cylindrical chamber, a register ring plate encircling the cylinder to cover the inlets to said air entry ducts, a burner pot mounted in the bottom of said chamber, and an oil feed pipe leading to said burner pot from the outside of the cylindrical chamber. 5 10

2. An oil fuel burner comprising a horizontal cylindrical burner chamber having a closed front 15 end and an open rear end and provided with a top opening, a lid covering said top opening, said lid having an air entry aperture therein of flat triangular form extending transversely of the axis of said cylindrical chamber and taperingly 20 decreasing in area from the exterior inwardly, said cylindrical chamber also being provided near its rear end with a number of air entry ducts disposed at circumferentially spaced intervals and opening radially into the cylindrical chamber, a register ring plate encircling the cylinder 25 to cover the inlets to said air entry ducts, a burner pot mounted in the bottom of said chamber, and an oil feed pipe leading to said burner pot from the outside of the cylindrical chamber. 30

3. An oil fuel burner comprising a horizontal cylindrical burner chamber having a closed front end and an open rear end and provided with a top opening, a lid covering said top opening, said cylindrical chamber also being provided near its rear end with a number of air entry ducts disposed at circumferentially spaced intervals and opening radially into the cylindrical chamber, a register ring plate encircling the cylinder to cover the inlets to said air entry ducts, a burner pot mounted in the bottom of said chamber, an oil feed pipe leading to said burner pot from the outside of the cylindrical chamber, a cylindrical casing extending around the front end and cylindrical wall of the burner chamber in spaced 45 relation to said chamber, and means on the exterior of said casing forming air entry passages extending upwardly from the sides of said casing and into the top thereof. 50

4. An oil fuel burner comprising a horizontal cylindrical burner chamber having a closed front end and an open rear end and provided with a top opening, a lid for covering said top opening, said lid having an air entry aperture therein, said chamber near its rear end being formed with an annular enlargement provided with a number of air ducts extending in from its front face and opening into the interior of the cylindrical chamber, a register ring plate encircling the cylindrical chamber against said front face of said enlargement, a cylindrical casing extending around the front end and wall of the cylindrical chamber in spaced relation thereto and enclosing also said annular enlargement, said casing having air entry passages passing upward on its outside 60 walls and extending into the top thereof, a burner pot mounted in the bottom of said chamber, and an oil feed pipe leading into the burner pot from the outside of the cylindrical chamber. 65
